[57] CLAIM

The ornamental design for a bicycle fairing, substantially as shown.

DESCRIPTION

FIG. 1 is a left front perspective view of a bicycle fairing showing my new design;

FIG. 2 is a left side elevational view thereof, the right side being a mirror image of the left side shown herein;

FIG. 3 is a top plan view thereof;

FIG. 4 is a bottom plan view thereof;

FIG. 5 is a front elevational view thereof; and

FIG. 6 is a rear elevational view thereof.
